(57) **CLAIM**

The ornamental design for a support arm with an extension, as shown and described herein.

DESCRIPTION

FIG. 1 is a front perspective view of a support arm with an extension, in a lower position.

FIG. 2 is a rear perspective view thereof.

FIG. 3 is a top view thereof.

FIG. 4 is a right side view thereof.

FIG. 5 is a front view thereof.

FIG. 6 is a left side view thereof.

FIG. 7 is a bottom view thereof.

FIG. 8 is a front perspective view of the support arm with an extension, in a horizontal position.

FIG. 9 is a rear perspective view thereof.

FIG. 10 is a top view thereof.

FIG. 11 is a right side view thereof.

FIG. 12 is a front view thereof.

FIG. 13 is a left side view thereof.

FIG. 14 is a bottom view thereof.

FIG. 15 is a front perspective view of the support arm with an extension, in an upper position.

FIG. 16 is a rear perspective view thereof.

FIG. 17 is a top view thereof.

FIG. 18 is a right side view thereof.

FIG. 19 is a front view thereof.

FIG. 20 is a left side view thereof; and,

FIG. 21 is a bottom view thereof.

The broken lines in the drawings depict portions of the support arm with an extension and form no part of the claimed design.

1 Claim, 21 Drawing Sheets
